UNITED STATES PATENT OFFICE.

ERNEST W. EKSTRAND, OF SANTA MONICA, CALIFORNIA, ASSIGNEE TO ALHAMBRA KILNS, INC., OF LOS ANGELES, CALIFORNIA, A CORPORATION OF CALIFORNIA.

MEANS FOR FORMING ROOFING TILE.

Application filed August 24, 1926. Serial No. 131,165.

This invention relates to a means for forming roofing tile.

For many years roofing tile of the mission type have been formed manually by forming 5 the clay into a slab, which slab has been bent around the form, such as a tree trunk, or, as the old California Indians manufactured the same, around the thigh. With increasing demand for these roofing tile, the old manual 10 means have proven inadequate to supply the demand. Competition in the manufacture of these roofing tile has also become keen so that it has become necessary to provide crude methods and means for the manufacture 15 thereof. In the manufacture of these mission tile, it is essential that the tile be formed to approximately semi-circular cross-section and that the same taper from the larger to the smaller end thereof substantially uniform 20 and that the tile when formed are substantially uniform so as to enable the laying of the same on the roof. It is also important in the manufacture of these tile, that the handmade texture of the exterior of the same 25 be maintained or very closely approximated so that the same will have the appearance of the ancient handmade tile, such as were employed upon the roofs of the old missions and haciendas as built by the Franciscans in the 30 latter half of the eighteenth century, in order that the same will find a ready market in the reproduction of the building or structures of the Spanish or Franciscan architecture.

35 The invention embodied in the present application is addressed to the provision of apparatus wherein a thin ribbon of clay, first mixed to the proper consistency, is delivered to an apparatus which automatically cuts the ribbon into desired lengths and these cut slabs of clay are then delivered or positioned over saddles or molds of the desired curvature, which slabs or molds are then moved to a second means which cuts away the surplus 40 clay along the edges of the saddles so that the slabs will exactly fit the same, all to be performed without the employment of an undue amount of manual labor, and so performed as to retain upon the exterior of the roofing tile 45 formed a texture which closely approximates that formed by the ancient processes.

Other and more particular objects of this invention will be apparent from the following detailed description of a preferred embodiment.

ment thereof, as illustrated in the accompanying drawings, in which drawings:

Figure 1 is a top plan view of an apparatus for carrying out the method embodying this invention, illustrating the clay mixing or conditioning means as partly broken away. 60

Figure 2 is a side elevation thereof partly in vertical midsection.

Figure 3 is a rear elevation of a slab trimming means embodied in this invention.

Figure 4 is a front elevation of an extruding die embodied in this invention. 65

In the preferred embodiment of this invention, illustrated in the accompanying drawings, A illustrates a clay mixing and conditioning apparatus in which clay, after having 70 been dug from the ground, is mixed with water to the proper consistency so as to be extruded from a die or extruding means B in the form of a thin ribbon. The clay is preferably mixed in the conditioning means A to 75 such a consistency that the same is not so hard that it will crack on bending but of such a consistency that the same will not split on the mold. This consistency is found to be intermediate between that which is known in 80 industry as "stiff" and "soft mud", or approximately twenty-five per cent water.

In accordance with the method embodying this invention, the thin ribbon of clay, on leaving the extruding means B, passes 85 through a cutting means C by means of which the same is cut to the proper lengths to fit saddles D on which the slabs of clay are 90 slid. The slabs of clay are picked up with the saddles or molds D and are delivered to a trimming means E by means of which the slabs are trimmed at the edges of the saddles so that the same accurately fit the saddles. The slabs of clay are delivered from the means 95 E on the saddles D to stands F, on which stands F moisture is applied to their surface and the same are lightly kneaded with the hands to produce the proper exterior texture to approximate that produced in accordance with the ancient processes of molding the 100 same over tree trunks or thighs.

The mixing or conditioning means A may be of any desired or preferred construction, such as is commonly manufactured, and which includes a pair of augers 1 mounted 105 within a casing 2 and from which casing 2 the clay, properly mixed with the water by means of the augers 1, is forced into a neck

3 into the extruding throat 4, to the advanced end of which an extruding die 5 of the extruding means B is secured. The die 5 has a rectangular opening 6 formed therein of the 5 cross-section desired for the ribbon 7 which is extruded therethrough. The ribbon 7 leaves the die 5 and passes onto a plate 8 which is supported on a frame 9, which frame 9 is secured to uprights 10. The ribbon of 10 clay 7, as the same passes onto the plate 8, passes over a lubricating well 11 in which a lubricating roller 12 is mounted. The lubricating well 11 is filled with a light lubricating oil which is transferred by means of the 15 roller 12 to the undersurface 13 of the ribbon 7 so as to prevent adhesion of the ribbon 7 to the plate 8. The plate 8 is preferably formed of brass or a like material, polished so that the ribbon 7 will slide easily there- 20 over.

Means are provided adjacent the die 5 for retaining and confining the ribbon 7 as the same is extruded through the die 5, which means are preferably of the following construction:

Releasably secured to the frame 10 at the opposite sides thereof are a pair of arms 14, which arms 14 are secured at their opposite ends to a hold-down retaining plate 15 which 30 is pivotally positioned in position by means of the arms 14, which are pivotally secured to the frame 9 at 16 so that the plate 15 rests by gravity upon the ribbon 7 as the same passes therethrough. The sides of the arms 35 14 form side retaining bands which retain the sides of the ribbon 7 in position as the same passes under the gravity hold-down plate 15.

Means C are provided in advance of the 40 hold-down plate 15 for cutting the ribbon 7 into slabs of the length of the saddles D, which means are preferably of the following construction:

Uprights 17 are secured to the opposite 45 sides of the frame 9 and a shaft 18 is journaled in these uprights 17 at the upper ends thereof.

Mounted upon the shaft 18 and rigidly secured thereto is a ceramic roller 19 which is 50 mounted in position to ride upon the upper surface 20 of the ribbon 7. Secured to the shaft 18 at the opposite ends of the ceramic roller 19 are a pair of outwardly extending arms 21, which arms 21 are provided at their 55 outer ends with a cutting member 22, which cutting member 22 preferably constitutes a stiff wire which is strung between the arms 19 and is held in tension by any suitable locking means, such as illustrated at 23.

60 The slabs of clay, passing under the ceramic roller 19, pass outward onto the end portion 24 of the brass band 8, upon which position the same are slid along the plate 8 and over the saddle D, which saddle D is mounted intermediate tapered side guides 25

so that its uppermost surface 26 is parallel or below the surface of the plate 8.

After the cut slab is positioned over the saddle D, the saddle D is lifted from the groove formed between the side guides 25 70 and transferred to the trimming means E upon which the slab is slightly kneaded to make the same accurately fit the saddle D. The saddle D is preferably formed of any suitable or desirable material, such as cast 75 aluminum, wood, or the like, and is hollow and is tapered from its larger end 27 to its smaller end 28. Mounted in the inside of the hollow member, of which the saddle D is formed, are guides 29, upon which the slabs 80 and saddles are supported on race bars 30 mounted in spaced relation along a support 31.

Mounted at the rear of the race bars 30 is a trimming member 32, which trimming 85 member 32 is preferably a wire which is strung between supporting arms 33 mounted at the ends of the support 31 and at an elevation to correspond with the lower edges 34 of the saddles D so that after the slab of 90 clay has been kneaded to the contour of the saddles D, the saddles D are drawn rearward by means of hand handles 35 so that their lower edges 34 pass over the cutting element 32 so as to trim the clay along the 95 edges 34 to make the same accurately fit the saddles D.

After the slabs of clay have been positioned and formed to the curvature of the saddles D and have been trimmed, the saddles D 100 with the slabs thereon are moved to kneading stands F wherein water or moisture is supplied to their exterior surfaces 36 so as to fill the pores that may be formed therein and the exterior surfaces 36 are preferably 105 kneaded with the hands so as to make the surfaces 36 irregular so that the same will accurately correspond with the ancient texture produced upon the old mission tiles as used on the roofs of the early California 110 missions and haciendas.

Having fully described a preferred embodiment of my invention, it is to be understood that I do not wish to be limited to the exact details herein set forth which may 115 obviously be varied without departing from the spirit of my invention as set forth in the appended claims.

I claim:

1. In an apparatus for forming tile, the 120 combination of means for mixing clay with water, a die secured to the said mixing means and through which the said clay is extruded as a ribbon, a plate mounted adjacent the said die, means mounted above the said plate 125 for cutting the said ribbon to form slabs of predetermined length, a saddle mounted below the surface of the said plate and onto which the said slab is slid, the said saddle having a handle by means of which the said 130

slab and saddle are lifted, and trimming means over which the said saddle is drawn to trim the edges of the slabs so that the said slab fits the saddle.

- 5 2. In an apparatus of the class described, the combination of clay conditioning and mixing means for extruding the said clay in the form of a ribbon, cutting means mounted

adjacent the said extruding means for cutting the said ribbon to form slabs of predetermined length, saddles onto which the said slabs are slid, and means for trimming the said slabs at the edges of the said saddles.

Signed at Los Angeles, Calif., this 14 day of August, 1926.

ERNEST W. EKSTRAND.
